UNITED STATES PATENT OFFICE.

LOUIS TOMCHIN, OF BROOKLYN, NEW YORK.

DESIGN FOR A FINGER RING.

Application filed March 25, 1927. Serial No. 21,327. Term of patent 3½ years.

To all whom it may concern:

Be it known that I, LOUIS TOMCHIN, a citizen of the United States, residing at Brooklyn, in the county of Kings, city and State of New York, have invented a new, original, and ornamental Design for Finger Ring, of which the following is a specification, reference being had to the accompanying drawing, forming part thereof.

Figure 1 is a side view of the ring, show-

ing the design in detail on substantially one-half of the right-hand side of the ring, the same being repeated on the left-hand side; and

Figure 2 is an edge view thereof.

I claim:

The ornamental design for a finger ring, as shown and described.

LOUIS TOMCHIN.
